UNITED STATES PATENT OFFICE.

WILLIAM G. KENDALL, OF NEWARK, NEW JERSEY.

VANITY CASE.

1,409,867.

Specification of Letters Patent. Patented Mar. 14, 1922.

Application filed March 13, 1921. Serial No. 452,812.

To all whom it may concern:

Be it known that I, WILLIAM G. KENDALL, a citizen of the United States, and a resident of Newark, in the county of Essex and State of New Jersey, have invented new and useful Improvements in Vanity Cases, of which the following is a full, clear, and exact description.

The object of the invention is to provide certain new and useful improvements in vanity cases whereby the interior of the case body is divided and means are provided for securely holding two porcelain or similar disks or carriers carrying different cosmetics, such, for instance, as rouge and compact face powder.

Another object is to permit of readily placing a partition in position in a vanity case and securely holding it therein.

Another object is to dispense with glue, cement or similar adhesive material for fastening the disks or cosmetic carriers in position.

Another object is to allow of cheaply and accurately manufacturing the partition.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a plan view of the improved vanity case with the cover in open position and with the front wall of the case body shown in section;

Figure 2 is an enlarged cross section of the same on the line 2-2 of Figure 1;

Figure 3 is an enlarged longitudinal section of the same on the line 3-3 of Figure 1; and

Figure 4 is an enlarged perspective view of the partition.

The body 10 of a vanity case is provided with a hinged cover 11 and is arranged to contain two porcelain disks or similar carriers 12 adapted to support the rouge, compact face powder or other cosmetics 13. In order to securely hold the cosmetic carriers 12 in position in the vanity case body 10 and to allow of replacing the same by others after the cosmetic has been used up, the following arrangement is made: Within the

case body 10 fits a partition 15, preferably made from a single sheet of metal or other material bent to provide a transverse wall 16 doubled up to form vertical members 17 40 from the lower end of each of which extends integrally a horizontal segmental flange 18. From the segmental edge of each flange 18 extends integrally upward a segmental clamping band or arm 19 having its ends 20 45 projecting beyond the flange 18 and engaging the peripheral edge of the corresponding cosmetic carrier 12 at the front and rear thereof. Each end 20 has a projecting top portion 21 bent inwardly to engage the top 70 of the corresponding cosmetic carrier 12, to securely hold the cosmetic carrier in position in the case body 10.

From the top edge to the middle of each clamping band 19 extends integrally a downwardly bent lug 25 terminating at its lower end in a longitudinally extending arm 26 having its end terminating in an upwardly bent lug 27. The arm 26 is adapted to support the corresponding cosmetic carrier 12 75 and its lugs 25 and 27 engage the peripheral face of the said carrier 12 at the sides thereof. By the arrangement described each cosmetic carrier 12 is held in place against transverse or longitudinal movement by the 80 ends 20 of the clamping bands 19 and by the lugs 25 and 27 of the arm 26 resting on the bottom of the case body 10.

In order to fasten the partition in place in the case body 10, the front and back of the case body are each provided with inwardly struck-up lugs 30 and 31 overlying the front and rear portions of the horizontal flanges 18 of the partition 15 to hold the partition against upward movement in the case 95 body 10.

From the foregoing it will be seen that the partition 15 can be readily placed in position within the case body 10 with the lugs 30 and 31 sprung over the bottom 100 flanges 18. It will also be noticed that after the partition has been placed in the case body 10 the cosmetic carrying disks 12 can be readily placed in position and held in place by the clamping bands 19 and by the 105 lugs 25 and 27 of the arms 26 on which rest the said disks. It will further be noticed that glue, cement or similar adhesive materials are not required for fastening the cosmetic carrying disks 12 in position in the 110 case body 10. The partition 15 on account of being made of one single piece of sheet

material can be very cheaply manufactured and by its arrangement it does not in the least obstruct access to the cosmetics carried by the disks 12.

5 Having thus described my invention, I claim as new and desire to secure by Letters Patent:

1. In a vanity case, a partition made of a single piece of material comprising a 10 doubled-up partition wall, bottom flanges extending in opposite directions from the members of the said wall, and clamping bands rising from the said flanges and having their free ends projecting from beyond 15 the flanges to engage the cosmetic carriers held in the case.

2. In a vanity case, a box body having inwardly struck-up lugs, a partition made of a single piece of sheet metal, comprising a 20 doubled-up transverse wall, the members of which are provided with segmental horizontal bottom flanges adapted to rest on the bottom of the body of the vanity case and adapted to be engaged by the said lugs to 25 hold the partition in place, segmental clamping bands extending integrally upward from the side edges of the said bottom flanges, the free ends of the said clamping bands being adapted to clampingly engage the peripheral 30 faces of cosmetic carrying disks at the front and rear thereof, the ends having inwardly projecting members engaging the top of the cosmetic carrying disks, and longitudinal 35 arms extending integrally from the said segmental bands and on which are adapted to rest the said cosmetic carrying disks, the ends of the said longitudinal arms having upturned flanges engaging the peripheral 40 face of the said disks at the sides thereof.

4. The combination with a vanity case, of a removable partition in the case, oppositely extending base flanges integral with the partition, arcuate spring clamping arms integral with the base flanges, and adapted to embrace cosmetic carriers in the case, said arms including reduced extensions at their 45 free ends adapted to retain said carriers against movement.

5. The combination with a vanity case, of a removable partition in the case, arcuate spring arms integral with opposite sides of the partition, longitudinally extending arms integral with the intermediate portions of 50 the arcuate arms, said longitudinal and arcuate arms adapted to co-act in holding cosmetic carriers within the case.

6. The combination with a vanity case, of a removable partition in the case, arcuate 55 spring arms integral with opposite sides of the partition, longitudinally extending arms integral with the intermediate portions of the arcuate arms, said longitudinal and arcuate arms adapted to co-act in holding cosmetic carriers within the case, and means 60 at the free ends of all the arms adapted to engage with carriers in the case.

WILLIAM G. KENDALL.
